DESIGN FOR A COMBINED SALT AND PEPPER SHAKER

Howard L. Ross, New York, N. Y.

Application September 9, 1942, Serial No. 108,160

Term of patent 7 years

To all whom it may concern:

Be it known that I, Howard L. Ross, a citizen of the United States, residing at New York, in the county and State of New York, have invented a new, original, and ornamental Design for Combined Salt and Pepper Shakers, of which the following is a specification, reference being had to the accompanying drawing, forming a part thereof.

In the drawing:

Fig. 1 is a side perspective view of a combined salt and pepper shaker, showing my design; and

Fig. 2 is a front perspective view thereof.

Fig. 3 is a perspective view of the pepper shaker element as it appears when removed from the remainder of the article; and

Fig. 4 is a perspective view of the salt shaker element as it appears when removed from the remainder of the article.

Fig. 5 is a bottom perspective view of the pepper shaker element illustrated in Fig. 3; and

Fig. 6 is a bottom perspective view of the shaker element illustrated in Fig. 4.

I claim:

The ornamental design for a combined salt and pepper shaker, substantially as shown.

HOWARD L. ROSS.
